UNITED STATES PATENT OFFICE.

PAUL J. HACKETT, OF SEATTLE, WASHINGTON, ASSIGNOR TO UNIVERSAL HIGH POWER TELEPHONE COMPANY, OF KING COUNTY, WASHINGTON.

UNIVERSAL SOUND-TRANSMITTING MEANS.

1,156,867.

Specification of Letters Patent.

Patented Oct. 12, 1915.

Application filed July 6, 1914. Serial No. 849,276.

To all whom it may concern:

Be it known that I, PAUL J. HACKETT, a citizen of the United States, and a resident of the city of Seattle, in the county of King and State of Washington, have invented certain new and useful Improvements in Universal Sound-Transmitting Means, of which the following is a full, true, and exact specification.

10 This invention relates to sound transmitting means and has for its principal object to improve the construction shown and described in my prior application for United States patent serially numbered 793,460 and filed on the fourth (4th) day of October, 1913, in that my present invention provides means for utilizing the potential of the human voice, for example, over a greater range of tones and over-tones than has heretofore been possible.

Other objects will appear as the invention is more fully hereinafter described, illustrated in the accompanying drawings and pointed out in the appended claims.

25 These objects are attained by the peculiar arrangement of associated stationary and moving electrodes in which one set of diaphragms, under the action of impinging sound waves upon their inner sides, increases the flow of current through their inclosed granule carbon variable resistance by compressing the said carbon, while the other set of diaphragms under the same influence has decreased the flow of current 30 through the inclosed carbon granules by reducing the pressure upon the same. In this peculiar arrangement any given diaphragm operates against the physical resistance of only one inclosed carbon element, instead of 35 two, as for instance that shown in my said prior application, and against this resistance only when moving in one direction, lessens the friction and restraint to free vibration, thereby making the diaphragm much more 40 sensitive to the impinging sound waves.

In the drawings, Figure 1 is a plan view with the outer casing removed. Fig. 2 is a side elevation of the same with the casing in place and looking in the direction of arrows *a a*. Fig. 3 is a section upon the line *x—x* of Fig. 1. Fig. 4 is a section upon the line *y—y* of Fig. 1. Fig. 5 is a wiring diagram of my device.

55 Referring now more particularly to the drawings, reference numeral 1 indicates a

tubular sound passage which is threaded to receive a mouthpiece 2. Extending radially from the said passage are similar passages 3, 4, 5, and 6. As sound waves are set up within the mouthpiece 2 and the passage 1, through the human voice or otherwise, the said waves are deflected equally into the passages 3, 4, 5 and 6 by reason of the pyramid 7 whose apex is coincident with the center of the tube 1. The four planes of the pyramid face the four passages 3, 4, 5, and 6 respectively, and the said pyramid is secured within a depression 8 in the joined tubes 3, 4, 5, and 6 by means of a screw 9. The outer ends of the tubes 3, 4, 5, and 6 respectively are threaded as shown to receive disks 10 and 10^a which are recessed as at 11 and 11^a, and the said disks may have holes 12, which may be larger than shown but are preferably of about the proportion 75 shown. The function of these holes is to clarify the sound transmitted by allowing the air to escape therethrough, rather than to return by way of the tubes 3, 4, 5 and 6, which return would cause interference with 80 entering sound waves. Bridges 13 and 13^a cross the centers of the disks 10 and 10^a, being secured thereto by screws 13^b. Within the recesses 11 and 11^a are diaphragms 14 and 15, respectively, having insulated bands 85 16 around their peripheries. The said diaphragms are depressed centrally as at 14^a and 15^a, and they are held in place by springs 17 which are secured to the disks 10 and 10^a by means of screws 18, the inner 90 ends of the springs 17 being insulated as at 19. Secured to the diaphragms 15 are mica disks 20 which are held by rings 20^a and fastenings 20^b. These disks cover the 95 depressions 15^a. Through the centers of each of the disks 20 passes a spindle 21 which has a head 22 to which is secured a carbon electrode 23. The spindle 21 passes through a suitable bore in a collar 24. The said collar has a head 25 which bears against the mica disk 20 and is held thereto by a nut 21^a on the end of the spindle 21, acting against the end of the collar 24. The collar 24 passes through a bearing 26 and is held in place by a set screw 26^a. The bearing 26 has a projection 26^b which passes through an opening in a bridge 13. The said bearing is insulated from the bridge by disks 13^c and is secured to the said bridge by 100 means of insulated screws 27. Through a 105

110

hole in the bottom of the depression 15^a a bolt 28 passes which has a head 29 and a nut 30 which serves to hold the bolt securely in place. Secured to the head of the bolt 5 is an electrode 31. Between the fixed electrode 23 and the movable electrode 31 are carbon granules 32. Secured to the bridges are terminal blocks 33 to which are secured terminal connections 34 and 35. It will be 10 readily understood that the electrode 23 is held stationary in the above mentioned case while the electrode 31 is movable, being held securely to the diaphragm.

Referring now more particularly to Figs. 15 1, 2 and 3, a case 36, having outstanding flanges 36^a and open at its inner side, has a mica disk 37 secured over the said opening by means of a ring 38 and fastenings 38^a. The said case, disk and ring are supported 10 from and secured to the diaphragm 14 by tubular supports 39 which are positioned between the ring 38 and diaphragm 14. Passing through the flanges 36^a, disk 37, ring 38, tube 39 and diaphragm 14 are bolts 25 40 having nuts 41, said bolts and nuts holding the above mentioned parts securely together. The cases 36 are provided with bolts 28, nuts 30 and electrodes 31, substantially as the depressions 15^a are provided. Disks 30 37 are connected to spindles 21 having heads 22 and nuts 21^a, electrodes 23 and collars 24, substantially the same as the disks 20. Carbon granules 32 separate the electrodes 23 and 31. Collars 24 are secured to the bridges 35 13^a by means of screws 27. The said collars are insulated from the bridges by the insulations 13^c. By reference to Fig. 3 it will be readily understood that the electrode 23 is stationary and the electrode 31 is movable, being connected to the diaphragm as described above. The four disks 10 and 10^a are secured to a circular casing member 42 by screws 42^a, which is in turn secured to a stand 43. The outer casing 44 incloses all 45 the mechanism of the device and is secured to casing member 42 by means of screws 45.

Referring now to the wiring diagram in Fig. 5, diaphragms 14 are connected electrically with the electrodes 31, which are connected by wires 46 and 46^a to wires 47 and 47^a, which in turn are connected to the diaphragms 15. The said diaphragms are electrically connected to their electrodes 31. Wires 47 and 47^a lead, one to each pole of a 50 dynamo 48. Electrodes 23 are connected in pairs by wires 49 and 50 and 49^a and 50^a respectively. One each of the diaphragms 14 and 15 are connected by means of wires 50 and 50^a to the primary windings 51 of 55 an induction coil 51^a, the latter co-acting with a secondary coil 52 terminating in wires 53 which lead to the receiving end of a telephone system, not shown.

The operation of the device is as follows:—When sound waves are set up with-

in the mouthpiece they travel downwardly and are equally deflected by the pyramid 7 to the tubes 3, 4, 5, and 6, whence they travel to the respective diaphragms 14 and 15 against which they impinge, causing the 70 said diaphragms to swell outwardly which causes the granules 32, which are associated with the diaphragm 15, to be compressed between the electrodes of that diaphragm causing the granules to cohere to a greater 75 degree than when the said diaphragms are at rest. The swelling action of the diaphragms 14, on the other hand, causes its granules 32 to be compressed to a less degree than normal, with the result that the 80 electrical current which was previously equally divided in its flow through the course outlined to diverge unequally, the greater portion thereof taking the course of least resistance through the granules 85 which have just been pressed together by the said movement of the diaphragm 15, thence the greater part of the current flows through the wire 49, wire 47, diaphragm 15, electrode 31, granule 32, electrode 23, bolt 90 21 and wire 50 to the primary windings 51, returning through the wire 50^a, bolt 21, electrode 23, granules 32, electrode 31, diaphragm 15 and wire 47^a to the dynamo 48.

The device is the application of a Wheat- 95 stone bridge with a resistance cup in each of the four limbs, a source of current bridged between two opposite junctions of the resistance elements, and a primary bridged between the other two junctions. Normally, 100 no current flows as all the limbs are balanced but by the variation in resistance of the various branches due to the action of the diaphragms, the balance is destroyed and current flows through the primary first in 105 one direction and then in the other.

From the foregoing it will be seen that, due to the fact that the carbon resistance cells, formed by the casings 36 and by the central depressions in the diaphragms 15, 110 are so arranged that when sound waves swell the diaphragms outwardly, there is physical resistance offered by the granules to one diaphragm of each pair, but on the return movement or vibration of these diaphragms to which physical resistance has just been offered there is no physical resistance whatever because there are no granules on that side of those diaphragms, in contradistinction to such construction as 115 120 that shown, for example, in my said previous application serially numbered 793460, wherein there is physical resistance to the vibration of the diaphragms at all times. My present construction, therefore, is much 125 more sensitive than the construction last mentioned. It will be understood that in my present construction the diaphragms must be arranged in pairs, the diaphragm 14, for example, being the complement of 120

the diaphragm 15, and so on, and each diaphragm of each pair must, obviously, swell outwardly from the common source of sound, and, electrically considered, each diaphragm is oppositely disposed to its mate.

It will be noted that the holes 12 pass through that portion of the disks 10 and 10^a which is substantially parallel with the diaphragms 14 and 15. I am aware that it is common in the art to provide such holes as this, but not located in the same relative position with respect to the diaphragms as are the holes 12; that is to say, in an ordinary telephone transmitter slots or holes occur through the sides of the mouthpiece which permit the air to escape before it can reach the diaphragms at all. The holes 12 are, therefore, purposely cut through the disks 10 and 10^a and not through the side of the mouthpiece, so that the sound waves will surely strike the diaphragm first and then rebound out through the holes 12, which would not be the case if the said holes were in the mouthpiece proper.

I have shown and described a particular form of embodiment of my invention but am aware that many changes therein will readily suggest themselves to others without departing from the spirit and scope of the invention.

What I claim as new and desire to protect by Letters Patent is—

1. The combination in an electrical sound-transmitting device having a plurality of sound tubes communicating with a common source of sound, of a plurality of diaphragms arranged in pairs, a granule resistance cell mounted upon each diaphragm, and a fixed and movable electrode within each of said cells whereby the granules associated with one diaphragm only of each pair are acted upon by the outward swelling of that diaphragm.

2. The combination in an electrical sound-transmitting device having a plurality of sound tubes communicating with a common

source of sound, of a plurality of diaphragms arranged in pairs, a granule resistance cell mounted upon each diaphragm, and a fixed and a movable electrode within each of said cells whereby the granules associated with one diaphragm of each pair only are compressed by the outward swelling of that diaphragm and the corresponding granules of the other diaphragm of that pair are allowed to move away from each other.

3. The combination with a telephone transmitter of the type having a plurality of tubes communicating with a common sound passage and a diaphragm for each tube, of means for increasing the sensitiveness of the diaphragms, said means including an arrangement of the diaphragms in oppositely disposed pairs, a granular resistance cell affixed to each diaphragm and a fixed and a movable electrode within each of said cells whereby when sound waves impinge against any of the said pairs of diaphragms one diaphragm of each pair compresses the granules within its resistance cell and the other diaphragm of that pair loosens the granules within its cell.

4. The combination with a telephone transmitter having a common sound passage and diaphragms, of means for increasing the sensitiveness of the diaphragms, said means including an arrangement of the diaphragms in oppositely disposed pairs, a granular resistance cell affixed to each diaphragm and a fixed and a movable electrode within each of said cells whereby when sound waves impinge against any of the said pairs of diaphragms one diaphragm of each pair compresses the granules within its resistance cell and the other diaphragm of that pair loosens the granules within its resistance cell.

PAUL J. HACKETT.
